WASHING MACHINE

Louis Zimark, Syracuse, N. Y., assignor to The Prosperity Company, Inc., Syracuse, N. Y., a corporation of New York

Application April 25, 1938, Serial No. 204,026

4 Claims. (Cl. 68—207)

This invention relates to washing machines, and has for its object a construction by which a fluid or a liquid can be supplied to the inside of a washing machine, or the clothes container thereof, through a stationary set of jet openings. It also has for its object the location of the jet openings in the door through which the interior of the machine or the clothes container is accessible, for the purpose of loading and unloading.

10 More specifically, the invention relates to washing machines of the type in which a clothes container or drum is mounted in a casing to move about a horizontal axis and has an axial loading door opening at one end aligned with a door opening in the casing, the latter being closed by a door having an opening and closing movement, and more specifically, the object is a door construction formed or provided with a passage or passages through which a fluid or liquid can be 15 projected into the clothes container.

The fluid or liquid may be steam, water with or without soap or solvent, a dry-cleaning solvent, rinsing water or solvent, and air.

The invention consists in the novel features 25 and in the combinations and constructions hereinafter set forth and claimed.

In describing this invention, reference is had to the accompanying drawings in which like characters designate corresponding parts in all the 30 views.

Figure 1 is a perspective view of the type of washing machine embodying this invention with the fluid supplying door in open position.

Figure 2 is an outer face view, partly broken 35 away, showing the fluid chamber of the door.

Figure 3 is an edge view looking downwardly, partly in section, of parts seen in Figure 2, the contiguous portion of the outer casing and inner cylinder being also shown.

10 designates the outer washer casing, the upper portion of which is usually semi-cylindrical. 2 designates the clothes container or perforated drum, which is mounted in the upper portion of the casing to move about a horizontal axis.

15 This movement may be oscillatory, rotary, or reversible rotary movement, that is, a movement consisting of a plural number of revolutions first in one direction and then in the other.

In machines of this type, the clothes container 20 or drum is mounted on an axle at one end thereof which is journalled in suitable bearings in the rear wall of the casing, and the actuating movement is imparted to the axle from suitable actuating mechanism. The other end of the 25 drum is provided with an axial loading door open-

ing aligned with a door opening in the front wall 4 of the outer casing 1. The door opening in the container is provided with a suitable door frame 3 and the door opening of the casing is provided with a frame 5. Also, preferably the door frame 3 is provided with an annular flange 6 extending toward, and preferably, partly into the frame 5. Usually the end of the container or drum remote from that supported by the axle, that is, the end of the container 2 overhanging 10 in the casing 1 is supported on suitable bearings on the inner side of the front wall 4 of the casing. The bearings here illustrated consist of an outer bearing ring 7 secured to the frame 5 on the inner side thereof and arranged concentric 15 with and spaced from the periphery of the flange 6, and anti-friction bearings, as rollers 8, between the ring 7 and the periphery of the flange 6.

9 designates the door through which the interior of the container 2 is accessible for the 20 purpose of loading and unloading. The door has an opening and closing movement, and the feature of the invention is that a fluid or liquid can be supplied to the container or the interior of the casing through a passage or passages in 25 the door.

In the illustrated embodiment of my invention, the door is provided with a series of passages or jet openings arranged to discharge into the interior of the container 2 and the fluid or 30 liquid is supplied to said jet passage or passages through a feeder passage also formed in the door. As here illustrated, the door is provided with an annular series of jet openings, and the feeder passage is annular or arcuate, and is common to all of the jet openings or passages. 35

In the illustrated embodiment of my invention, the door 9 consists of an outer annular frame and a central panel 10 usually of glass suitably mounted in the frame, and the frame has an annular or cylindrical portion or flange 11 extending into the opening formed by the flange 3 of the container 2 or into the annular flange 6 of the frame of the door opening of the container 2. As the container 2 is moving about its axis, the annular portion or flange 11 preferably does not contact the flange 6 but a suitable clearance is left to permit a free movement of the drum about its axis. The door 9 is hinged to the frame 5, and as here shown, the annular frame thereof is provided with laterally extending hinge-leaves 12 which are hinged by means of hinge-pins 13 to hinge-leaves 14 provided on the frame 5 of the door, opening in the front wall of the casing 1. 15 designates a series of jet openings or pas-

5 sages here shown as formed in the ring 9^a constituting a cover for a feed passage or header formed in the flange 11, the jet openings being arranged to discharge into the container 2 through the door opening formed by the flange 6, the series being here illustrated as arcuate or annular. The fluid or liquid is supplied to the jet openings at the will of the operator through conduit means including a feed passage or header formed in the door. The header 16 is common to all the jet openings 15. The conduit means also includes a passage 17 extending in a general tangential direction from the annular passage 16 lengthwise of one of the hinge-leaves 12 and it 10 communicates with a conduit 18 connected to a suitable source of supply, as a pipe 22 connected to a valve 20. The conduit 18 is connected to the door frame 9 in communication with the passage 17 through a suitable coupling 19 located near 15 the axis of the hinges. Preferably, the section of this conduit 18 adjacent the door is flexible to permit the opening and closing of the door. The flow of fluid through the conduit 18 is controlled by a suitable valve 20 mounted on the machine 20 in any convenient location.

25 The jet openings 15 may be directed into the drum or container 1 at any desired angle or angles most suitable to effect the washing, rinsing or treating of the articles in the container 2 while such articles are being tumbled by the movement of the container about its axis, and the direction and force of the jets may be such as to break up any rolling, balling or roping effect of the clothes, particularly when the drum is being 30 rotated in one direction only.

35 The actuating mechanism is usually located in the lower part 24 of the casing.

40 As this general type of machine forms no part of this invention and is well-known, and further as the invention relates to the projecting of water through the loading door, it is thought that further description of the washing machine is unnecessary.

45 What I claim is:

1. In a washing machine of the type having an outer casing, and a container mounted to rotate about a horizontal axis in the casing and having an axial loading door opening in one end thereof and the casing having a door opening alined with that of the container; the combination of a door for the opening in the casing, the door having an opening and closing movement 50

and including an outer frame, and a panel supported by the frame, the frame being formed with a passage arranged to discharge into the container, and conduit means for supplying liquid to said passage.

2. In a washing machine of the type having an outer casing, and a container mounted to rotate about a horizontal axis in the casing and having an axial loading door opening in one end thereof and the casing having a door opening alined with that of the container; the combination of a door for the opening in the casing, the door having an opening and closing movement and having an annular portion on the inner side thereof extending into the door opening of the container, the door also having a passage in said annular portion arranged to discharge into the container, and conduit means for supplying a liquid to said passage.

3. In a washing machine of the type having an outer casing, and a container mounted to rotate about a horizontal axis in the casing and having an axial loading door opening in one end thereof and the casing having a door opening alined with that of the container; the combination of a door for the opening in the casing, the door having an opening and closing movement and including an outer frame, and a panel supported by the frame, the frame having an annular portion extending into the opening of the container, the door having a transverse passage through said annular portion arranged to discharge into the container, and conduit means for supplying a liquid to said passage.

4. In a washing machine of the type having an outer casing, and a container mounted to rotate about a horizontal axis in the casing and having an axial loading door opening in one end thereof, the casing having a door opening alined with that of the container, the combination of a door, the door having an opening and closing movement and also closing the axial door opening of the container, the door being provided with means forming an annular conduit provided with jet openings at the margin of the inner face of the door arranged to discharge into the container through the loading door opening when the door closes both door openings, and conduit means for supplying a liquid to said annular conduit.

50 LOUIS ZIMARIK.
